ANTENNA ELEMENT

James W. Collins, Buchanan, and Harold G.
Murphy, Peekskill, N. Y.

Application March 9, 1950, Serial No. 148,622

1 Claim. (Cl. 250—33)

1

This invention relates to antenna elements, particularly those elements used in forming antenna structures for receiving short wave transmissions in the television, frequency modulation and ultra-short wave range, and the method of making such antenna elements as an article of manufacture.

An object of the present invention is to provide a novel antenna element which is an improvement over the extruded tubular elements now used in forming most short wave or television receiver antenna structures.

Another object of the invention is to provide a novel, simple and economical method of producing the present improved antenna element.

A further object of the invention is to provide an antenna element which is light in weight, highly resistant to bending stresses, and low in cost, at the same time presenting no curtailment in efficiency as a collector of high frequency oscillations.

Still another object of the present invention is to provide an antenna element which may be formed in a large variety of lengths and sizes and which may be used as masts and cross supports in antenna structures, as well as receiving elements, and which are particularly adapted to be used with a suitable insulator such as described in our co-pending application for Antenna for the Reception of High Frequency Oscillations, Serial No. 148,621, filed on even date herewith.

A further object of the present invention is to provide an antenna element which when used in plural sets in an antenna structure results in a minimum of vibration and whistling, reducing breakage due to crystallization and metal fatigue.

Still another object of the invention is to provide a tubular antenna element which because of its core will not collect water, thus eliminating the bursting of the antenna element due to the freezing and expansion of collected water and further eliminating the need for flattening or sealing of the tube end as in the hollow, extruded tubular element to prevent condensation therein.

A further object of the present invention is to provide an antenna element so formed in a variety of ways such as a butting or overlapping split tube, laminations, coiled spring wire or longitudinal folded ribs, that the element may expand radially due to temperature expansion or ice pressure from capillary water without rupturing the casing, and return to its original shape when such pressure is relieved.

Another object of the present invention is to provide an antenna element that is considerably

2

more resilient than the extruded tubular element usually used, and which may bend under heavy ice or wind loads and return to an original position without rupture of the casing.

5 A further object of the present invention is to provide an antenna element that is formed with a metal casing and dielectric core, such as wood, plastic or the like, said core being treated to prevent moisture absorption, and which element may 10 permit the core to extend beyond the metal casing if desired to serve as an insulator for clamping the elements in a holding block of non-insulating material.

A final object of the invention is to provide an 15 element which may be cheaply fabricated by rolling in length or diameter or by dies in a power press and in which the core may be anchored or attached in various ways to the metal casing.

With the above and other objects in view, as 20 will become presently apparent, the invention consists in general of certain novel details of construction and combinations of parts hereinafter fully described, illustrated in the accompanying drawings, and particularly claimed.

25 In the drawings, like characters of reference indicate like parts in the several views, and

Figure 1 is an elevation showing one method of 30 fabricating the elements, as by rolling in length or diameter, and filling the outer tubing with a core and tightly joining the tube on the core;

Figure 2 is a sectional perspective of one form 35 of element;

Figure 3 is a view similar to Figure 2 of another form or modification of the element;

35 Figure 3a is a section taken on the line 3—3 of Figure 3; and

Figures 4, 4a, 5, 6, 7 and 8 are views similar to Figures 2 and 3 of further forms or modifications of the element.

40 Referring to the drawings in detail, in Figure 1 is shown one method of fabricating antenna elements of the present invention, in which a flat ribbon or strip 10 of dural or other conducting metal highly sensitive to energization for sound

45 and picture receiving of different wave lengths from different directions, is placed or fed from a strip, roll or reel onto a table 11 and from thence, forward between coacting interfitting forming rolls 12 and 13 placed one above the other and rotatable about their axes 14 and 15 held in suitable bearing supports. Roll 12 is shown provided with

50 one or more reduced portions 16 into which the flanged periphery or annular conforming and overlapping edge portions 17 of roll 12 extends to 55 partially bend the marginal longitudinal edge

portions of narrow sheet or strip 10 up in offset curved fashion by a jog therein at and between the rolls 12 and 13, as shown at 18. The strip 10 may be fed simultaneously with a rectilinear core 19 thereon centrally of its width, so as to be partially bent up against the core. Core 19 is of uniform cross-section throughout its length and suitable electrical insulating material, such as wood, plastic, or even metal of solid, tubular or laminated form, or plastic wood to fill the completed outer tube of the element.

The strip and core are then fed forward from rolls 12 and 13 between similarly mounted and journaled additional mating rolls 20 and 21 of similar formation peripherally except that they may be differently proportioned in size and diameter and overlap to turn the edges of the strip 10 up further in coiled form, as indicated at 22, so that the longitudinal, marginal edges of the strip 10 are brought toward each other in closer relation on and about the core 19 but still in slightly separate relation to each other. After this, the strip and core are run between similarly mounted coacting circumferentially or peripherally concaved rolls 23 and 24, which turn the strip edges further to extend entirely around the core with their edges meeting and in contact to form a tubular shell about the core. The edges may be left in abutment as formed or joined in any suitable way, as by welding, soldering, or otherwise, along the joint 25 formed by the meeting edges of the formed tube 26 which is of uniform cross-section throughout its length so that the core 19 and the tube 26 will snugly interfit each other throughout the length thereof.

As shown in Figures 1 and 2, the tube 26 along the marginal abutting edges of the joint or seam 25 may be indented as at 27 in one or more rows of indentations to push the same into the core, as at 28, and effectively anchor the tube to the core against separation, shifting movement or displacement relative thereto. This may be accomplished in any suitable way, as by coacting concaved rolls 29 and 30 similarly journaled as the other rolls and provided with intermeshing circumferential peripheral teats, pins or projections on one or both rolls forcing the tube metal at such points into and forming depressions in the core with tight contact between the core and shell or tube. The tube and core may be of any suitable cross-sectional shape, and the tube wall of any thickness, and the tube enveloping the core may be deposited by electrolysis or plating, if desired. The core may be of natural wood, formed of plastic wood or any suitable plastic, or even metal, the latter being preferably, but not necessarily, a non-conductor of electric current, and may be solid, tube or laminated to give desired thickness and tensile strength, and all of any diameter suitable for the purpose.

In Figures 3 and 3a, the parts are similarly designated, but instead of anchoring the tube on the core as in Figures 1 and 2, the rolls 29 and 30 may be formed peripherally to produce elongated intermeshing lineal indentations 31 which may or may not enter depressions 32 or be depressed into the core 19.

In Figure 4 the indentations 27 are the same as employed in connection with Figures 1 and 2, but, in addition and instead of the edges of the strip shell or tube casing being brought into abutting relation and joined or otherwise fastened together or on the core, the edge margins are brought into overlapping relation, as indicated

at 33, and similarly fastened, if desired, as previously explained.

In Figure 5, the construction method and product article of manufacture is the same as in Figures 1 and 2, except that the rolls are formed to produce a tube 34 of rectangular and oblong cross-section with the sides bent at right angles relatively to snugly receive or fit the core 35 of similar cross-section. Flanges 36 along the marginal edges are brought together to form the seam 37 and anchored by similar indentations and depressions 27 and 28 as previously described, in the tubular shell and core, respectively.

In Figure 6, the tube 38 has the seam 39, and is fitted, formed or filled with core 40. However, in this instance, the tube is shown formed with longitudinal reinforcing ribs 41 which better allow for expansion of diameter and return to original shape. This tube may be anchored on the core by indentations 42 entering depressions 43 formed thereby in the core which has external ribs 44 longitudinally to enter the concavities of the ribs 41 on the inside.

In Figure 7, the tubing 45 is formed of a coil wound on or filled with core 46, and may be fabricated by the conventional method of telescoping or by coiling wire or strap stock around the core in compression therewith. In this form, the coils may form indentations or projections at the inside of the tube encircling the core and entering depressions or circumscribing annular or helical spiral grooves in the core periphery formed by pressing the helical coils of the tube, or by filling the tube with a plastic non-conductor, as heretofore described. It is also to be understood that in all the forms hereinbefore set forth, the tube may be filled completely with core to interfit at the indentations and depressions formed by the indentations at the inside of the tube entering the core at its periphery.

In Figure 8, a second coil or shell 47 with or without core 46, the same as in Figure 7, is coiled or fitted over the coil 45, forming a laminated covering or tube with plural layers, as may also be done with the other forms of the invention not formed of coils, but layers of sheet metal plied one on the other. Also, this form may be used with or without solid core 46, the inner coil serving as a hollow core.

The tube may be tempered as desired, and the core, especially of wood, can be coated or waxed to prevent moisture absorption, or the core may be treated in any suitable or well known way for this purpose. Also, an adhesive may be used to fasten the tube to the core, especially where the tube is too thin to firmly grasp and conform to the core tightly and stay tightly thereon.

In Figure 4a, the tube 26 and core 19 are the same as in Figures 1, 2, 3 and 4, except that the joint may be a reinforcing and stiffening rib 48, as in Figure 6, running longitudinally, and formed by a rolled lap or lock joint 49 at the marginal edges of the metallic sheet or strip sealed at the inside as at 50 to hide and cover any raw or exposed edges of the strip.

In all forms, the element is of light weight, strong and rugged, an excellent conductor, except the core which may be a non-conductor, and which may be extended from the tube and utilized as an insulator. The laminated or covered core construction results in superior strength over a simple tube, and may be used in proper sizes or diameters and wall thicknesses, as a mast

or cross support for antenna as in our co-pending application filed on even date herewith, or in stacking one antenna on another supported by cross support bars on the mast to which they are secured. Moreover, the core prevents the tube from crystallizing and breaking due to vibration and metal fatigue in wind, and since it is impossible for the tube to collect water on the inside to freeze and crack the element, as a result of condensation, as is the case with tubing alone, no flattening of the tube ends or use of plugs therein is necessary to seal the ends of the tube or give additional strength. The tubes can be fabricated as described by rolling or turning in connection with Figure 1, or by rolling in length or diameter by rolls or discs, or progressive dies, in a power press, and with the tube or casing completely or partially surrounding the core. The element may also be formed of a spring or group of laminated springs, one within and in contact with the other, and so wound as to be rigid enough to hold its own weight and more. The advantage is that a heavy ice load which would break or destroy a hollow tube, would cause such spring elements to sag instead of breaking or permanently bending, and when the ice melts, the element would return to its original straight and true rectilinear form.

While there is herein shown and described the preferred embodiment of the invention, it is nevertheless to be understood that minor changes may be made therein without departing from the spirit and scope of the invention as claimed.

What is claimed as new is:

As a new article of manufacture, an antenna

element for receiving short wave transmissions in the television, frequency modulation and ultra-short wave range, comprising an elongated electrical conducting tubular shell of uniform cross-section throughout its length and a dielectric core therein and snugly and tightly interfitting within the tube throughout their lengths, said shell being anchored at closely spaced points throughout its length to the core and being provided with longitudinal reinforcing and stiffening formations, said reinforcing and stiffening formations being ribs located on the core and channels within the shell snugly interfitting thereon and thereby completely filling the shell.
